TUBING HANGER

Frank E. Cobb, St. Louis, Mo.

Application December 30, 1938, Serial No. 248,411

4 Claims. (Cl. 248—58)

This invention pertains to a support or hanger for tubes, bars or other similar articles.

One of the objects of this invention is to provide a hanger of simple construction adapted to support a plurality of members such as tubes, bars or the like, and which may be easily assembled with the members to be supported and secured in assembled relation.

Another object is to provide such a hanger which may be constructed of light material and yet be strong and rigid in use.

Another object is to provide a simple hanger of separable parts which may be assembled by a combined lateral and longitudinal movement, and which when locked against one of said movements will be secure against the other.

Further objects will appear from the following description taken in connection with the accompanying drawing in which

20 Figure 1 is a side view of a hanger embodying this invention shown in assembled relation.

Figure 2 is a similar view showing the separate parts disassembled.

Figure 3 is a plan view of Figure 2.

25 Figure 4 is a plan view of Figure 1 and

Figure 5 is a fragmentary sectional view taken about on line 5—5 of Figure 4 illustrating an arrangement of the hanger for suspending the same from a support.

30 The hanger of this invention is intended primarily for use in supporting the coils of tubing such as are used in refrigerating apparatus. It may, however, be applied to other uses whereby members of the nature of tubes or bars are to be supported or secured in assembled relation.

35 Referring to the drawing, the hanger is made in a pair of complementary parts as shown in Figure 2, which parts may be of identical construction. In the embodiment illustrated the two 40 parts are identical and each comprises a channel shaped member indicated generally at 1 and having a web 2 and flanges 3. The flanges 3 are provided with a series of aligned openings or notches 4 extending angularly with respect to the longitudinal axis of the channel. These notches are spaced apart along the elements 1 according to the spacing desired for the members supported which in the illustration are pipes 5.

45 The holding elements 1 may be constructed of sheet material. It has been found that these elements when constructed of comparatively light sheet aluminum provide a strong and rigid support for refrigerator coils.

50 In applying the hanger to the members to be supported said members are assembled in the

notches 4 of one of the elements 1 as shown at the left hand side of Figure 2. The second element 1 is then assembled in inverted relation with respect to the first element and is moved into assembled position by a combined downward 5 and lateral movement as indicated by the arrows in Figure 2, so that each of the notches 4 embraces one of the members 5. Thus the second element operates to close the notches 4 of the first element to secure the members 5 therein 10 as shown in Figure 1.

Both elements may be provided with perforations 6 which, when the two elements are in assembled relation as shown in Figure 1, are positioned to receive a locking element such as a 15 cotter pin 7. One or two securing elements 7 usually may be employed. It will be noted that when only one is used the hanger is still securely locked in assembled relation, since the overhanging ends 8 of the flanges are so positioned that 20 when the elements 1 are secured against end wise movement relatively to each other, sidewise movement is prevented by engagement of the parts 8 with the members 5.

When the hanger is assembled as shown in 25 Figure 1, it provides not only a locked holder adapted to secure the members 5 in their established positions, but also to provide a stand upon which the coil of tubing of which said members may be a part may rest as on feet. The 30 hanger may also be arranged to suspend the coil from an overhead support, as shown in Figure 5, in which the locking element 7 may take the form of a bolt passing through an eye bolt 9 or other suitable suspending device by means of 35 which the hanger may be attached to an overhead support.

It will be seen that this invention provides a holder or hanger for such members as tubes or bars which may be very cheaply constructed of 40 sheet material, as the form illustrated lends itself readily to manufacture by stamping operations. While constructed of light material, the complementary elements 1, when in assembled relation, support each other in such fashion that a 45 strong and rigid support is provided. It will be understood, of course, that while in the illustration the two elements 1 are identical in form, this is not essential but one may be of different form than the other as, for instance, to provide for 50 attachment to a support, so long as the arrangement of the notches is such as to provide for assembly as described.

It is obvious that various changes may be made in the details of construction within the scope 55

of the appended claims without departing from the spirit of this invention, and that the invention is not limited to the specific details shown and described.

5. Having thus described the invention, what is claimed is:

1. A hanger of the character described, comprising, a pair of channel-formed holding elements having substantially identically arranged angularly extending sockets in their flanges, and means for securing said elements together in relatively inverted position with their flanges interplaced.
15. A hanger of the character described, comprising, a pair of holding elements of sheet material formed to channel form, sockets in the flanges of said elements extending angularly thereof, said sockets having the same spacing and the same angularity in both said elements,
20. and means for securing said elements together in inverted relation.

3. A hanger of the character described, comprising, a pair of complementary holding elements provided with oppositely-facing elongated sockets having obliquely extending entrance passages into which the members to be supported are insertable by lateral and longitudinal movement relative to said elements so that each member occupies sockets in both said elements, and means for securing said elements against one of said movements relative to each other. 5

4. A hanger of the character described, comprising, a pair of complementary holding elements provided with oppositely-facing, elongated, open-ended sockets extending obliquely with respect to said elements, said sockets being so positioned that each pair thereof may be closed about a member to be supported by lateral and longitudinal movement with respect to each other so as to embrace and hold the member. 10
